RAZOR STROP

Filed Feb. 19, 1930

F. K. Hehnly, INVENTOR
BY Victor J. Evans

ATTORNEY

UNITED STATES PATENT OFFICE

FRANK K. HEHNLY, OF ST. PETERSBURG, FLORIDA

RAZOR STROP

Application filed February 19, 1930. Serial No. 429,642.

This invention relates to new and useful improvements in a razor strop and has for its primary object the provision of razor honing and finishing elements shaped and mounted to permit of a razor being honed and finished with a keen or proper shaving edge in a manner similar to the stropping of a razor on a hand strop.

Another object of this invention is the provision of a honing plate and a finishing plate that are arranged parallel and have at one end support attaching means and at the other end a hand grip to permit a person to sharpen a razor in the usual stropping manner.

15 A further object of this invention is to provide a razor strop of the above named character which shall be simple, durable and efficient and which may be manufactured and sold at a comparatively low cost.

20 With these and other objects in view as will become more apparent as the description proceeds, the invention consists in certain novel features of construction, combination and arrangement of parts as will be hereinafter 25 more fully described and claimed.

For a complete understanding of my invention, reference is to be had to the following description and accompanying drawings, in which:—

30 Figure 1 is a side elevation illustrating a razor strop constructed in accordance with my invention.

Figure 2 is an edge elevation illustrating the same.

35 Figure 3 is a sectional view taken on the line 3—3 of Figure 1.

Figure 4 is a perspective view illustrating one of the clamps.

40 Figure 5 is a perspective view illustrating one of the members of the other clamp of my invention.

Referring in detail to the drawings, the numeral 1 indicates an elongated honing plate preferably constructed from slate and 45 is positioned upon a spacing strip or pad 2 constructed from canvas or any other material suitable for the purpose.

A finishing plate 3 constructed preferably 50 of glass is positioned against the opposite side or face of the pad or strip 2 from the

honing plate 1 and is of a corresponding size to the honing plate. The strip or pad 2 projects beyond one of the ends of the plates 1 and 3 as clearly shown in Figure 2 and has mounted thereon leather pieces 4 to form a 55 hand grip 5 and the latter has its side edges cut away as clearly shown in Figure 1 so that a person may readily obtain a firm grip thereon. The hand grip 5 is detachably secured to the sharpening plates 1 and 3 by a 60 clamp 6 which includes a pair of gripping plates 7 that are apertured as shown at 8 to receive fastening screws or elements 9 to firmly connect the plates 1 and 3 to the hand grip 5. The fastening elements 9 are preferably 65 in the form of male and female members having threaded connection with each other and provided at their outer ends with slotted head portions to receive a screw driver or similar element for tightly securing the 70 gripping plates 7 upon the sharpening plates 1 and 3 and the hand grip 5. The gripping plates 7 have their side edges bent inwardly to form stop flanges 10 that abut the ends of the plates 1 and 3 when the clamp is assembled. The ends of the plates 7 are bent inwardly to form end flanges 10 adapted to be engaged over the edges of the plates 1 and 3 thus cooperating with the flanges 10 in preventing the gripping plates from moving 80 sidewise on the sharpening plates 1 and 3.

The leather pieces 4 are secured together and to the extended ends of the pad or strip 2 by stitching as clearly shown in Figure 1.

A clamp 11 is detachably secured to the 85 other ends of the plates 1 and 3 and the pad or strip 2 by fasteners 12 similar in construction to the fasteners 9 and has connected thereto a snap hook 13 whereby the device may be conveniently attached to a permanent 90 support and suspended therefrom. The snap hook 13 is secured to a ring 14 which in turn is swivelly connected to the clamp 11 to permit a person to easily turn the device so that either the plates 1 or 3 may be disposed uppermost for running a razor thereover in the usual stropping manner. The clamp 11 is constructed from a single piece of material, preferably metal which is cut away to form 95 a web portion 15 that supports the parallel 100

and relatively spaced gripping portions or plates 16 to receive therebetween the ends of the plates 1 and 3 and the pad or strip 2. The plates 16 have their side edges bent inwardly to form flanges 17 adapted to engage the sides of the plates 1 and 3 as clearly shown in Figure 2.

In use with the device attached to a suitable support (not shown) through the medium of the snap hook 13, a person grips the handle 5 in one hand with the plate 3 constructed from slate disposed uppermost and with the other hand runs a razor backward and forward over the plate 3 to hone the razor and after the razor has been properly honed the device is reversed and the plate 1 constructed of glass and disposed uppermost and the razor is then moved backward and forward thereover so as to put a very keen or shaving edge thereon.

While I have shown and described the preferred embodiment of my invention, it will be understood that minor changes in construction, combination and arrangement of parts may be made without departing from the spirit and scope of the invention as claimed.

Having thus described my invention, what I claim is:

A razor strop comprising sharpening and finishing plates of glass and slate respectively, a padding member positioned between the plates and at one end thereof projecting beyond the plates, said padding member adapted to cushion the plates and aid in preventing breaking of the plates, hand grip elements positioned against opposite faces of the extended portion of the padding member and stitched thereto, clamping plates positioned against the sharpening and finishing plates adjacent one of their ends and having inwardly extending side and end flanges and said end flanges engaging over the edges of said sharpening and finishing plates and the side flanges engaging the hand grip elements, fasteners securing the clamping plates together and causing the side flanges to bite into the hand grip elements, and a clamp securing the sharpening and finishing plates together at the other ends thereof.

In testimony whereof I affix my signature.

FRANK K. HEHNL
